UNITED STATES PATENT OFFICE.

VICTOR R. HEFTLER, OF DETROIT, MICHIGAN, ASSIGNOR TO SOCIETE DU CARBURATEUR ZENITH, OF LYON, FRANCE, A CORPORATION OF FRANCE.

STOP LEVER.

Application filed December 3, 1920. Serial No. 428,164.

To all whom it may concern:

Be it known that I, VICTOR R. HEFTLER, a citizen of the United States, residing at Detroit, county of Wayne, and State of Michigan, have invented a new and useful Improvement in Stop Levers, of which the following is a full, clear, and exact description.

The present invention relates broadly to stop levers and more particularly to levers of this type adapted for use in connection with throttle shafts of carburetors and the like.

The principal object of the present invention is to provide a sheet metal lever particularly adapted for use with carburetors, and provided with a frictionally held adjusting device.

Another object of the present invention is to provide a sheet metal stop lever having one end thereof bent to form a fixed stop, and the other end bent to receive an adjustable screw and a spring arm co-operating therewith to hold the screw in the desired position.

The foregoing and other objects, together with their attendant advantages, will be apparent as the invention becomes better understood, by reference to the accompanying specification and drawings forming a part thereof, it being premised that changes may be made in the various details and the manner of operation, within the scope of the appended claims, without departing from the spirit of the invention.

Figure 1 is a side elevation, partly broken away, of a portion of a carburetor having my improved stop lever applied thereto;

Figure 2 is a side view of the construction illustrated in Figure 1;

Figure 3 is a top plan view of the stop lever shown in Figure 1.

Referring more particularly to the drawing, there is illustrated a sheet metal stop lever comprising an apertured main body portion 1, having secured thereto in any desired manner a hollow steel hub 2, adapted to receive a tapper pin or key 3 for attaching the lever to a throttle shaft or the like 4. From the main body portion 1 radiate an arm 5 having its outer end bent inwardly to form a fixed stop 6, and a second arm 7, carrying an adjustable stop screw 8.

For receiving the stop screw 8 the arm 7 is formed with an angular tongue 9, the outer end of which is rolled upon itself to

form a hollow cylinder 10, internally screw threaded to co-operate with the screw 8. It will be apparent that both the fixed stop 6 and the adjustable stop 8, are adapted to engage a suitable projection 11 secured at any desired position to the carburetor casing; the stop 6 limiting the opening movement of the throttle shaft and the stop 8 limiting the extent of closing movement thereof.

In practice it has been found necessary to provide some means for holding the adjustable stop in its adjusted position. This has heretofore been accomplished by lock nuts and the like requiring the use of a separate tool for tightening or loosening the same, but in the present case the arm 7 is provided with a projection 12 having an offset portion 13 bent to underlie and extend substantially parallel to the screw 8. The offset portion 13 is provided with an opening within which is riveted a housing 14 for the friction pawl 15 carried by a stem 16 and normally projected upwardly into engagement with the knurled head 17, on the screw 8, by a compression spring 18. The stem 16 may extend through the bottom of the housing 14 and have a head 19 formed thereon to prevent accidental loss of the pawl 15.

With the construction described, it will be obvious that there is provided an inexpensive sheet metal stop lever construction which may be easily produced by stamping and which readily adapts itself to the purpose intended.

The advantages of the present invention arise from the provision of frictional retaining means carried by the lever and enabling an easy adjustment of the movable stop while preventing the accidental movement thereof.

Further advantages of the invention arise from the sheet metal construction having a separate hub secured thereto, whereby strength and simplicity are obtained at a minimum cost.

I claim:

1. A stop lever, comprising a sheet metal body having an arm projecting outwardly therefrom, a tongue on said arm rolled upon itself to form a hollow cylinder, screw threads in said cylinder, a screw adjustably co-operating therewith to form an adjustable stop for said lever, a projection on said lever extending substantially parallel to the longitudinal axis of said screw, a housing

- secured to said projection, and a spring device within said housing for maintaining said screw in adjusted position, substantially as described.
5. 2. A stop lever, comprising a sheet metal body having an arm projecting outwardly therefrom, a tongue on said arm rolled upon itself to form a hollow cylinder, screw threads in said cylinder, a screw adjustably 10 co-operating therewith to form an adjustable stop for said lever, a projection on said lever extending substantially parallel to the longitudinal axis of said screw, and provided with an opening therein, a housing secured in said opening, and a spring device carried by said housing for maintaining said screw in adjusted position, substantially as 15 described.
3. A stop lever comprising a sheet metal body having a pair of arms extending angularly therefrom, an integral fixed stop car-
- ried by one of said arms, an adjustable stop carried by the other of said arms, said last mentioned arm having an integral projection and means carried by said projection 25 and cooperating with said adjustable stop for holding the latter in adjusted position, substantially as described.
4. A stop lever comprising a sheet metal body having a substantially flat intermediate portion provided with a throttle shaft receiving opening, a separate hub secured to said body portion and having an opening lining with the opening therein, said body portion having an arm extending angularly 30 therefrom and forming a fixed stop, a second arm extending angularly therefrom, and an adjustable stop carried by said second arm, substantially as described.

In testimony whereof I have hereunto set 40 my hand.

VICTOR R. HEFTLER.
